UNITED STATES PATENT OFFICE.

JAMES F. MAYS, OF BIRMINGHAM, ALABAMA, ASSIGNOR TO MAYS ACCOUNTING MACHINE COMPANY, OF ASHEVILLE, NORTH CAROLINA, A CORPORATION OF NEVADA.

LISTING MECHANISM FOR TYPE-WRITING MACHINES.

1,182,500.

Specification of Letters Patent.

Patented May 9, 1916.

Application filed November 12, 1914. Serial No. 871,757.

To all whom it may concern:

Be it known that I, JAMES F. MAYS, a citizen of the United States, residing at Birmingham, in the county of Jefferson and 5 State of Alabama, have invented certain new and useful Improvements in Listing Mechanism for Type-Writing Machines, of which the following is a specification.

This invention relates primarily to improvements in that class of devices the object of which is to insure with the least possible thought or effort on the part of the operator of a typewriter that a printing operation shall start at a given point on 5 the paper, other than at the commencement of the normal carriage travel, such devices being chiefly useful in typewriting columns of figures, particularly columns of figures representing amounts of money where the 0 starting of the printing operation with respect to the position of the decimal point is material as, for example, in listing the amounts of checks.

My invention in this connection embodies 5 not only improved means for determining the starting point of the type printing or writing operation, but it also embodies in conjunction therewith mechanism for rotating the platen of the typewriter and shifting 0 it laterally into the proper printing position, and so disposing the two such mechanism with relation to each other that the two may be simultaneously operated by one hand of an operator. This is particularly 5 useful when the listing mechanism is used on a typewriter operated from a calculating machine placed alongside the typewriter, since the operator may then use one hand to operate the keys of the calculating machine and the other to manipulate the listing machine.

My invention embodies also mechanism for causing the typewriter to print a decimal point at the proper place automatically and as an independent operation. I am aware that it is old in listing machines to have a decimal point cut on the same type with a digit and therefore when the digit is printed, the decimal point is printed also, but my invention provides mechanism for printing the decimal in a separate operation from that of printing the digit.

The mechanism here shown was devised especially for use on a typewriter operated from an adding or calculating machine

placed alongside the typewriter, but it should be understood that I do not so limit its application, since it will be readily seen that it may be used on a typewriter whether the latter be operated from a calculating 60 machine or not.

In order to more fully describe my said invention, reference will be had to the accompanying drawings which show a specific embodiment thereof, and, wherein— 65

Figure 1, is a fragmentary top plan view of a typewriter equipped with my improved listing mechanism; Fig. 2, a sectional elevation showing the electromagnetically operated mechanism for the automatic 70 operation of the typewriter for printing a decimal point; Fig. 3, a sectional elevation showing parts of my improved mechanism as viewed from the rear of the typewriter; Fig. 4, a fragmentary transverse sectional 75 elevation of my said mechanism shown in connection with portions of the typewriter; Fig. 5, a detail section on line 5^x—5^x Fig. 4; Fig. 6, a detail perspective view of a portion of the platen rotating mechanism; Fig. 80 7, a detail section on line 7^x—7^x Fig. 1; Fig. 8, a fragmentary detail section on line 8^x—8^x Fig. 3; Fig. 9, a side elevation of one of the listing key levers removed from the other portions of the mechanism; Fig. 10, 85 a front elevation of parts of my improved listing mechanism; Fig. 11, a detail section taken on line 11^x—11^x Fig. 10, and Fig. 12, a detail section of the electrical contact mechanism taken on line 12^x—12^x Fig. 10. 90

In the accompanying drawings, I have shown my invention as applied to an L. C. Smith typewriter, model No. 5, though I do not wish to be understood as limiting it to that or any other particular make of 95 typewriter machine.

The machine to which I have here shown my invention applied employs the usual cylindrical platen 1, mounted for rotation on its longitudinal axis in a carriage 2, adapted 100 to travel horizontally back and forth past the printing point. Various parts of the typewriter, not immediately associated with my invention, are omitted for the sake of clearness and as being unnecessary to a clear 105 understanding of my said invention.

In carrying out my invention as here shown, I employ mechanism for stopping the travel of the typewriter carriage and therefore the lateral travel of the platen at 110

predetermined points, which mechanism comprises, among other parts, a series of key levers 3 pivotally mounted upon spindle or stud 4 secured to a bracket 5, which is in turn secured to the lower side of a stationary bar 6. The bar 6 on the model of typewriter above referred to, constitutes the stationary tabulating bar of that machine, and, further than forming a convenient support for my attachment, is in no way related to my invention. The bar 6 constitutes a fixed portion of the machine and is rigidly mounted upon uprights 7 and 8, forming extensions of brackets 9 and 10 fixed to the top of the typewriter frame 11, back of the platen carriage.

Each key lever 3 is provided with an upward extension or key stem 12, upon the upper end of which is rigidly mounted a plate 13 upon which the finger of the operator is adapted to rest in operating a given key lever. Each of these plates 13 has an upward extension 14 on its left side, viewing the typewriter from the front, the function of which extensions will hereinafter more fully appear. These key levers are all mounted side by side and move in parallel vertical planes, and their key stems 12 are located at such distances respectively from the pivot support 4 as to be located in a row, the said stems being bent transversely as shown most clearly in Fig. 4, so that the finger tips of the key levers will all be in alinement. Each key stem 12 of said key levers extends through an individual slot in a casing 15 which incloses all of said levers, said casing being provided with a movable section 16 to permit it to be slipped over the levers. Each key lever 3 is also provided with a downward extension or lug 17, and these lugs are located respectively such distances from the point of pivotal support 4 as to be staggered with relation to each other, as shown most clearly in Fig. 3. The function of these lever extensions is to individually engage and operate a series of bell crank levers 18, pivotally supported upon a spindle 19 mounted in two uprights 20 and 21 of the bracket 22, fast to the back of the top frame piece 11 of the typewriter. The bell crank levers 18 are located in close proximity side by side, and move in parallel vertical planes between the uprights 20 and 21. The upright 21 is provided with an extension 23, which constitutes a guide for the vertical movement of key levers 3, and for this purpose each such key lever moves vertically in an individual slot in said extension. The lugs 17 of the key levers rest respectively upon the horizontal arms 24 of the bell crank levers 18, said arm of each such bell crank lever being held against its corresponding lug 17, under the tension of spring 25 (see Fig. 11).

65 Bell crank levers 18 are located side by

side in a row, so that each is a different distance from the central point of the typewriter carriage travel, the said distances varying uniformly and being engaged by the thickness of the bell crank lever. The 70 depending arm 26 of each of these bell crank levers constitutes a stop adapted to be projected into the path of some portion of the typewriter carriage 2, or body attached thereto, to limit the movement of said carriage in one direction so as to stop it at a given point.

In the machine to which I have here shown my invention applied, there is a bar 27 which is located on the rear of the typewriter carriage and on top of the machine, said bar being rigidly secured to the said carriage and therefore movable therewith. Further than constituting a stop to limit the carriage travel in one direction, this bar 80 forms no part of my invention. In other words, it is immaterial so far as my invention is concerned, what other function this bar may perform in the normal operation of the typewriter, it being sufficient to say that it forms a rigid part of the typewriter carriage.

On the finger plate of each key lever 3 is placed the character designating the position in which the carriage will be stopped, 90 if a given key is operated. When the attachment is used for listing or tabulating numbers with respect to a decimal point, the preferred designation of the respective keys will be by the characters ".00", "1", "2", "3", "4" and "5", as shown in Fig. 10.

If any of the keys indicated ".00", "1", "2", "3", "4" and "5," respectively be depressed, the extension 17 of the particular key lever operated will force the depending arm 26 of its corresponding bell crank lever into the path of the adjacent end of bar 27. Therefore, if the typewriter carriage be caused to travel from left to right the required distance, said bar will engage said lever arm and be stopped at that point. When the key indicated ".00" is depressed, the carriage will be stopped in a position to print figures on the right of the decimal point; if the key indicated 1 be depressed, the carriage will be stopped in position to print a numeral in the units position on the left of the decimal point, and, likewise, the carriage will be stopped in positions to start the printing of numbers in the tens, hundreds, thousands, and tens of thousands, positions respectively, according to which of the keys 2, 3, 4 or 5, is depressed. For example, suppose we are tabulating or listing amounts in a column, and the first 110 amount is 35. In such case the listing key indicated ".00" would be depressed and the carriage moved along until bar 27 strikes the lever projected into its path by the operation of said key. The typewriter keys 115 120 125 130

are then struck to print the amount .35. Then suppose the next amount is 125.45. In this case, listing key "3" would be depressed and the typewriter carriage moved 5 to the right until it is stopped by the lever projected by the operation of key "3." Then, if the keys of the typewriter be struck to print 125.45, the printing will commence in the third decimal place to the left of the 10 decimal point. The bell crank levers 18 are all located so far to the right as regards the carriage travel as not to interfere with the travel of the carriage in performing its normal operation. It will be noted that in performing 15 this listing operation, it is necessary to move the typewriter carriage, each time a listing key is operated, to the right to bring it into proper position to start the printing operation, and, obviously, each 20 time a new number is to be printed, it is necessary to rotate the platen cylinder in order to space the paper up to a new position.

My invention embodies, in addition to 25 the mechanism for stopping the typewriter carriage at the proper point, mechanism for simultaneously moving the typewriter carriage laterally to bring it into the proper printing position and rotating the platen 30 to feed up the paper, the two mechanisms being so relatively situated that a person may operate the two simultaneously with one hand. This mechanism for moving the typewriter carriage and simultaneously rotating 35 the platen comprises in the case here shown, among other parts, a lever 28 angularly movable on the spindle or shaft 29 of the platen 1, and carrying a pivoted pawl 30 adapted to engage with the teeth of the 40 regular platen rotating ratchet 31. The angular movement of lever 28 is limited by a pin 32, thereon, engaging with shoulders at opposite ends of a peripheral slot 33 in the plate 34 mounted alongside lever 28, 45 and held in a fixed position by pins 35 and 36 fast to said plate and the frame of the typewriter carriage. Lever 28 terminates at its upper end in a thumb-piece 37, so shaped as to fit the thumb snugly and to 50 form a convenient bearing against which the thumb may be pressed to rotate the lever 28, as well as to push the platen carriage to the right. Lever 28 is rotated in the direction above stated, against the tension of a 55 spring 38 which returns it to its normal position when released by the operator.

For the purpose of releasing pawl 30 from ratchet 31 when it is desired to render the lever inoperative to rotate the platen, there 60 is pivotally mounted on said lever a small bell crank lever 39 having a finger piece 40 for operating it, and a lip 41 adapted to engage a pin 42 on pawl 30, and thereby lift said pawl from ratchet 31.

65 It is not necessary to alter or omit any of

the parts of the typewriter, hereinbefore mentioned, in equipping the same with my invention. As regards to the lever 28, and its associated parts, there is just sufficient space between ratchet 31 and the portion of 7 the carriage forming a bearing for the spindle 29 of the platen to accommodate lever 28 and stop plate 34.

One of the distinct advantages of my invention, as thus far described, is that the 75 operations rotating the platen, moving the carriage up to the proper stopping point, and the manipulation of the stop keys for determining the point where the carriage shall stop, may be readily performed by one 80 hand of the operator, leaving the other hand free for the handling of papers, or, in case the typewriter is employed in connection with a calculating machine from which the typewriter is operated, leaves one hand of 85 the operator free to retain the fingers of that hand in position on the calculating machine keyboard. There is a distinct advantage in being able to keep the right hand upon the keyboard of the calculating machine, in such 90 a case, in preparation for the next stroke while making the carriage shift with the left hand alone. If the right hand is taken from the said keyboard after each stroke, it requires an extra interval of time to select 95 and strike the proper keys for adding the succeeding item. It should also be noted that when the lever 28 is pressed upward to rotate the platen, it is positively stopped at the end of its movement and forms a rigid 100 handle, as it were, by which the carriage may be pushed to the right in bringing it into the proper stopping position. At the same time that the lever 28 is thus operated by the thumb, the forefinger of the same hand 105 is placed upon the desired stop key 13, and the hand is given a twist in an anti-clockwise direction, at the same time pressing the selected key down with the forefinger. It is in this operation that the upturned portions 110 of the stop keys serve their purpose. Such upturned portions constitute a resistance or bearing surface against which the forefinger presses when the hand executes the twisting movement to push the carriage 115 to the right. In actual practice, it has been demonstrated that the movement of the forefinger and thumb in this operation is almost, if not quite, as easy as the mere pressing of a key by the forefinger alone. It has 120 also been demonstrated that the hand does not tire with the movement, as it does where the hand is employed to grasp and work back and forth a lever against several pounds of resistance, as is required in the 125 operation of a common form of combined listing and adding machine.

The movement of the hand, in executing the above described operation in connection with my improved mechanism, is very 130

short and may be performed so rapidly that there is quite a saving of time over the method of manipulating a lever, as above set forth. As the range of movement of the carriage in tabulating a column of figures with this mechanism is small, keys 13 and lever 37 are always during such operation in reach simultaneously by one hand of the operator. In other words, there is no necessity to cause the carriage to travel so far to the left that an operator with his thumb on lever 37 could not reach with a finger of the same hand, the keys 13.

It should also be noted that my above described mechanism is all located on top of the typewriter, and at the right hand side of the same. It is a distinct advantage to have the stop keys located in this position, over having them located lower down on the front of the machine, as is done in some typewriter listing attachments. When at the top of the machine, the indicating figures on the stop keys stand out plainly before the eye of the operator and are substantially in line with the printing position, so that the operator does not have to shift the eye but very little in glancing from the printed figures to the keys. Moreover, by placing the stop keys as in my device, the finger movement of the hand to grasp the carriage to shift the same is utilized in reaching the stop keys.

The mechanism for automatically printing the decimal point comprises electro-magnetic means for operating the period key of the typewriter, and a special contact device for automatically controlling this operation. The immediate key operating mechanism comprises a magnet 43 fast to a bracket 44 secured in any suitable way to the lower portion of the typewriter frame, and having a plunger armature 45, preferably hollow to secure lightness, pivotally attached to the typewriter key lever 46 which operates the period type bar. The energizing circuit of this magnet includes a battery 47 or other suitable source of electric current, the frame of the typewriter, an insulated contact 48, and a contact 49 in permanent electrical connection with the frame of the machine, the circuit being normally broken at contacts 48 and 49. Contact 48 is formed on one end of a screw 50, mounted in an insulated bushing 51, carried by an arm 52, pivotally mounted upon a screw 53 secured to bracket extension 23. Screw 50 is provided with a milled nut 54, and also constitutes a binding post. The angular movement of arm 52 on its pivot is limited by a pin 55 fast to bracket 23, engaging with the walls of a slot 56 formed in an upward extension 57 of arm 52, said arm being under the tension of a spring 58 tending to rotate the same in an anti-clockwise direction, Fig. 10.

Contact 49 is formed on one end of a metal arm 59 pivotally mounted as at 60 on arm 52 and in permanent electrical connection therewith. Contact 49 is normally forced away from contact 48 under the tension of a spring 61 fast to arm 59, the movement of the latter being limited in a direction away from contact 49 by a pin 62. Formed on arm 59 is a beveled cam or tooth 63 which is located in the path of an oppositely directed beveled cam 64, mounted on bar 27.

When the typewriter carriage is moved to the right (Fig. 10) to bring the end of bar 27 against one of the stop levers 18, the beveled face of cam 64 will engage the beveled face of cam 63, but will not force contacts 48 and 49 into engagement with each other, owing to the fact that arm 52 will yield upward carrying with it both said contacts. When, however, the carriage travels from right to left, as it will do when the keys of the typewriter are struck to print the numerals, the vertical face of cam 64 will engage the vertical face of cam 63 and thereby rotate arm 59 on its pivot, which will force contact 49 into engagement with contact 48. The continued movement, however, of cam 64 in said direction will force arm 52 upward and permit said cam to pass cam 63. When contacts 48 and 49 are thus brought into engagement with each other, this completes the energized circuit of magnet 43, thereby causing the same to attract its armature 45 to operate the period key lever 46 of the typewriter. The tooth or cam 63 is so located that its operation by cam 64 will always occur at the proper time to cause the printing of the period between the units position and the first decimal position on the right thereof. Since this printing operation is entirely automatic, the operator does not have to pay the slightest attention to the printing of the decimal point. For example, if he desires to print 125.45, having pressed the "3" stop key and shifted the typewriter carriage to the stopping position, he merely strikes the typewriter keys 1, 2, 5, 4 and 5 in succession, and the decimal point will appear in the proper position, without his having to strike the period key of the typewriter. This is a very great practical advantage, particularly in operating a typewriter from the keys of a calculating machine placed alongside the typewriter, since such calculating machines are not equipped with keys for printing decimal points.

Cam 64 may be angularly adjusted on a pivotal support 65 in order to throw it down out of the path of cam 63, in case it is not desired to utilize it, and in such case said cam may be provided with extensions or arms 66 and 67 adapted to engage with bar 27 to limit its angular movement, extension 180

67 being useful in setting case 64 in the proper operating position.

If desired, there may be attached to the rear of the typewriter frame brackets 68 and 69 upon which may be mounted a roll of paper 70 in strip form, upon which the numerals may be printed where it is desired to merely make a list of the same, or to add up a column of figures. In such a case, 10 I may provide the usual paper holding shield 71 of the typewriter, with a paper guide adjacent its right hand end, and feed the paper to the platen from said roll through said guide. Such guide comprises 15 a narrow plate 72 having an offset blade 73 lying on the opposite side of shield 71 from plate 72 and connected to said plate by a neck 74 which extends through an opening 75 in the shield 71. (See Fig. 7).

20 The strip of paper from roll 70 passes over the regular shield 71 and beneath the blade 73 and is held against lateral movement by the neck 74 and a finger piece 76 on a spring wire 77. The blade 73 is provided with a 25 beveled or knife edge 78 which may be employed for severing the paper strip.

Having thus described a specific embodiment of my invention, it should be understood that the same is susceptible to modifications without departing from the spirit thereof.

What I claim is:

1. The combination with a typewriting machine having laterally movable printing platen and carriage for supporting the same, of travel limiting means for stopping the movement of said carriage in a predetermined position, comprising a series of movable stops and a series of key levers adapted 35 and arranged to operate said stops individually to project them into the path of a portion of said carriage to stop the travel thereof, each of said key levers being provided with a key stem having at its upper end a 40 finger bearing with an upward extension adapted to form a fulcrum or bearing for the hand of the operator in shifting said carriage.

2. The combination with a typewriting 50 machine having a laterally movable printing platen and carriage for supporting the same, of travel limiting means for stopping the movement of said carriage in a predetermined position, comprising a series of 55 movable stops consisting each of a bell crank lever, a series of key levers pivoted upon a stationary part of the machine and each having an extension adapted to engage and operate an individual one of said stops to 60 project them into the path of a portion of said carriage to stop the travel thereof, and a finger key carried by each of said key levers and arranged in a row extending substantially parallel to the path of the travel of 65 said carriage and located at the top of the

machine rearwardly of the path of said carriage travel.

3. In a typewriting machine having a laterally movable rotatable printing platen and a carriage for supporting the same, means for 70 rotating said platen and shifting said carriage, in combination with a series of keys mounted upon a fixed part of the machine and so located on the top of the machine that they and said platen and carriage operating 75 means may be reached and simultaneously operated by one hand of the operator, and means operative by said keys to stop the travel of said carriage at a predetermined point.

4. In a typewriting machine having a laterally movable rotatable printing platen and a carriage for supporting the same, means for rotating said platen, said means including a lever fulcrumed on said carriage and provided with an upwardly extending arm for operating said lever to rotate said platen and also for shifting said carriage, in combination with a series of keys so located that they and said platen operating lever may 90 be reached and simultaneously operated by one hand of the operator, and means operative by said keys to stop the travel of said carriage at a predetermined point.

5. In a typewriting machine having a laterally movable rotatable printing platen and a carriage for supporting the same, means for rotating said platen on its said axis, said means including a lever fulcrumed on said carriage and provided with an upwardly 100 extending arm having a thumb piece for operating said lever to rotate said platen and also for shifting said carriage, in combination with a series of keys so located on the top of the machine that they and said platen operating lever may be reached and simultaneously operated by one hand of the operator, each of said keys having a finger bearing provided with an upturned extension to form a fulcrum for the hand of the 105 operator in operating the thumb piece of said platen and carriage moving lever, and means operative by said keys to stop the travel of said carriage at a predetermined point.

6. A typewriting machine having a carriage which travels transversely thereof, manually operated selective means to limit the movement of said carriage in one direction of its travel, power operated printing means, and means operated by said carriage in traveling in the opposite direction to that in which it is limited by said selective mechanism to control the operation of said power means to cause the automatic operation of said printing machine at a predetermined point.

7. In a typewriting machine having a transversely movable carriage, mechanism to effect the printing of a decimal mark at 110

- a predetermined point, comprising an electro-magnet, operative connection between said magnet and the type which prints said mark, electric contacts, an electric circuit including the winding of said magnet and said contacts, and automatic means operated by the movement of said carriage to close said contacts at a predetermined point.
8. In a typewriting machine having a transversely movable carriage, manually operable key levers, and printing means operable by said key levers, mechanism to effect the printing of a decimal mark at a predetermined point, comprising an electro-magnet, operative connection between said magnet and one of said key levers, electric contacts, an electric circuit including the winding of said magnet and said contacts, and automatic means operated by the movement of said carriage to close said contacts at a predetermined point.
9. In a typewriting machine having a transversely movable carriage, manually operable key levers, and printing means operable by said key levers, mechanism to effect the printing of a decimal mark at a predetermined point, comprising an electro-magnet, operative connection between said magnet and one of said key levers, electric contacts, an electric circuit including the winding of said magnet and said contacts, and automatic means comprising a tripping device attached to said carriage and arranged to close said contacts at a predetermined point in the travel of said carriage in one direction only.
10. In a typewriting machine having an element which travels step-by-step transversely thereof, electrically operated printing means, and means operated by said element to control the operation of said printing means, comprising an electric contact, a yieldable arm on which said contact is mounted, a supporting member yieldably mounted on said arm, an electric contact carried by said supporting member, and tripping means carried by said traveling element of the typewriter, said tripping means adapted to operate upon said supporting member to close said contacts when traveling in one direction only.
- In testimony whereof I affix my signature in presence of two witnesses.
